C-CLAMP

Conrad J. Schroeder, Kansas City, Mo.

Application December 30, 1936, Serial No. 118,330

6 Claims. (Cl. 144—304)

My invention relates to clamps, and more particularly to adjustable C-clamps. It is a purpose of my invention to provide a clamp of the above mentioned character that is exceedingly strong in construction and which is so constructed that the adjusting means will not be injured in any manner by heat produced by a welding arc, or flame, and which will engage the parts that are being clamped flatly so that there will be no possibility of the clamping jaws tilting relative to the material clamped nor of the clamp slipping out of position due to any uneven engagement of the jaws with the work, or any so-called "walking" of the movable jaw on the work, as is the case with C-clamps now in use.

More particularly my invention involves a clamp of the above mentioned character that comprises a C-shaped, or yoke-like, body portion having a pair of legs, one of which provides a fixed jaw and the other of which provides means for mounting a jaw that is movable relative to the body portion, said movable jaw being so constructed as to have great strength and to engage the work flatly without any possibility of the jaw getting out of line, or tilting, and which is further so constructed that the adjusting means associated therewith will not be exposed to the flame, or arc, of welding apparatus, or similar heat producing means.

It is a further purpose of my invention to provide a clamp of the above mentioned character, in which the jaw that is movable relative to the C-shaped body portion comprises a housing for the adjusting means, being, preferably, made of a tubular character with a closed end wall forming one clamping jaw and with bearings provided therein for the adjusting means so that said adjusting means is rotatable relative to said jaw, one of said bearing portions being, preferably, provided at the opposite end of the tubular body portion from the closed end forming the clamping jaw.

It is still another purpose of my invention to provide a clamp of the above mentioned character in which the body portion of the clamp is pulled, or drawn, toward the tubular jaw member, instead of the tubular jaw member being pushed toward the jaw carried by the body portion, during movement of the parts toward clamping position, this providing a tension on the adjusting means, rather than a compression thereon, which will prevent bending of the adjusting means, which is usually made in the form of a screw. This is accomplished by providing a

bearing for the adjusting screw in the tubular jaw member and providing means for holding said tubular jaw member against rotation relative to the yoke-like body portion, this being accomplished by slotting the tubular body portion so that a leg of the C-shaped body portion passes through said slot and the tubular member is guided for longitudinal sliding movement relative to the C-shaped body portion. The screw-threaded member has screw-threaded engagement with one of the legs of the C-shaped body portion, and furthermore, preferably, has a bearing provided therefor in the inner face of the closed end wall of the tubular body portion of one of the jaws of the clamp. An advantage of this construction is that due to the flat engagement of the jaws with the work, it is not necessary to open the clamp as widely to release the same from the work, as where a swiveled jaw is provided that tilts as it is being released.

It is a further purpose of my invention to provide means for holding said screw-threaded adjusting means from endwise movement relative to the tubular body portion, which means comprises a detachable member whereby the device can be readily assembled.

Other objects and advantages of my invention will appear as the description of the drawing proceeds. I desire to have it understood, however, that I do not intend to limit myself to the particular details shown or described, except as defined by the claims.

In the drawing:

Fig. 1 is a view in side elevation of my improved C-clamp, partly broken away.

Fig. 2 is a section taken on the line 2—2 of Fig. 1.

Fig. 3 is a section taken on the line 3—3 of Fig. 1.

Fig. 4 is a fragmentary section taken on the line 4—4 of Fig. 2, but on an enlarged scale.

Fig. 5 is a fragmentary section taken on the line 5—5 of Fig. 1, but on an enlarged scale, and

Fig. 6 is a fragmentary section taken on the line 6—6 of Fig. 2, on an enlarged scale.

Referring in detail to the drawing, my improved clamp comprises a C-shaped, or yoke-like, body portion having the legs 10 and 11 and the connecting portion 12. The same may be made of any desired cross sectional shape, but is, preferably, made of substantially T-shaped cross section with a somewhat enlarged head portion 13 and an enlarged base portion 14 so as to make the body portion of the clamp of considerable strength. The leg portion 10 is somewhat thick-

ened and enlarged to provide a clamping jaw 15, which has a flat clamping face 16, while the leg 11 is provided with a rounded somewhat enlarged tubular end portion 17, which is provided 5 with an internally screw-threaded opening 18.

Screw-threadedly engaging in the screw-threaded opening 18 is a screw-threaded adjusting member 19 made in the form of a screw-threaded stem having an enlarged end portion, 10 or head, 20, which may be of rectangular cross section, as shown in the drawing, and which is provided with a transverse opening 21, through which the handle, or adjusting lever, 22 extends, the same being slidably mounted therein, as is 15 common with such handle members, and is provided with enlargements, or heads, 23 at the ends thereof to prevent disengagement of the same from the portion 20. The head portion 20 provides a shoulder, or abutment, at 24 on the adjusting member, while the screw-threads 25 on the screw-threaded stem 19 engage with the threads 26 in the opening provided in the tubular enlargement 17.

Mounted on the adjusting member is the tubular body portion 27 of a jaw member, which is provided with a closed end wall 28, providing a flat jaw portion that is adapted to cooperate with the jaw 16 to clamp any desired work, that is to be engaged by the clamp therebetween. The member 27, as will be evident from Fig. 3, is circular in cross section, being of a tubular character, and it is obvious that the thickness of the material of the tubular portion 27 can be varied as desired to obtain the desired strength for the member 27. It is, of course, desirable that the member 27 and the yoke-like body portion be of substantially the same strength so that neither of the two parts will be capable of damage by force exerted on the clamp by means of the handle 22 through the screw threaded adjusting member 19. It will also be noted upon reference to Fig. 3, that a slot 29 is provided, extending longitudinally of the member 27 that is of such width as to receive the enlarged portion 14 of the leg 11 of the body portion of the clamp therebetween so that said member 27 will be slidably engaged with said leg 11 of said body portion, or in other words, that said body portion may slide lengthwise in the slot thus provided, so 50 that said tubular body portion and said tubular member 27 will be held against relative rotation and will only be movable longitudinally relative to each other.

Upon reference to Fig. 6 it will be seen that the closed end wall 28 of the tubular member 27 is provided with a socket, or recess, 30 therein with which the reduced end 31 of the threaded adjusting member 19 is adapted to engage, said recess, or socket, 30, thus acting as a bearing for one 55 end of said member 19. It will also be noted upon reference to Fig. 4 that the opposite end wall 32 of said tubular body portion 27 is provided with an opening 33 therethrough, which rotatably receives the unthreaded portion 34 of the adjusting member 19, and that when the parts are in the assembled position ready for use, shown in the drawing, said end wall 32 will be located adjacent the shoulder, or abutment, 24. It will be further noted that the screw-threaded 60 stem 19 is provided with a transverse opening spaced from the shoulder 24, through which the cotter pin 35 extends, said cotter pin being of such size that it will not be sheared off by any strain that may be placed thereon in the operation of the device. It will thus be seen that the 70

tubular member 27 is held from endwise movement relative to the screw-threaded adjusting member, as it will be limited in its endwise movement by means of the abutment 24 and the pin 35. Also it will be noted that the proportion of the parts is such that the reduced end 31 will not extend to the bottom of the socket 30 when the shoulder 24 engages the end wall 32, thus preventing any binding of the screw-threaded stem 19 between the leg 11 and the end wall 28. 10

It will also be seen that, due to the provision of the slot 29 and the connection between the screw-threaded adjusting member, or screw-threaded stem, 19 and the tubular jaw member 27, the adjusting member will rotate in the bearings 31 and 33 as the same is rotated by means of the handle 22, thus moving the C-shaped body portion of the clamp relative to the tubular member 27 so as to draw the jaw 16 toward the jaw 28 when the handle 22 is turned in one direction, and push the C-shaped body portion in a direction such as to move the jaw 16 away from the jaw 28 when the handle 22 is rotated in the opposite direction. The portion of the stem 19 that lies between the end wall 28 and the leg 11 of the C-shaped body portion has no strain whatsoever thereon in the adjustment of the clamp into clamping engagement. Furthermore the tubular body portion completely shields the screw-threaded stem portion 19 from the heat of the welding arc, or welding flame, when the clamp is used in connection with welding apparatus, for which it is particularly useful, the large body of metal in the tubular body portion not only protecting the screw-threaded member against the direct flame, or arc, but dissipating the heat so that there will be no such a high temperature reached at said screw-threads as to in any way damage the same. Also it is noted that the flat faces of the jaws 16 and 28 will always be parallel to each other due to the slideable connection between the C-shaped body portion and the tubular body portion forming the two relatively movable parts carrying the jaws of the clamp. 30 35 40 45

What I claim is:

1. A clamp comprising a C-shaped frame having a fixed jaw on one of the legs thereof, the other leg having a portion provided with a screw-threaded opening, a screw extending through said opening, a longitudinally slotted tubular member having a closed end providing a jaw cooperating with said fixed jaw, the leg having the portion provided with the screw-threaded opening extending through the slot in said tubular member and cooperating with the walls of said slot to prevent rotation of said tubular member relative to said leg, said portion having said screw-threaded opening being mounted within said tubular member, said screw having one end thereof journaled in said closed end of the tubular member, said tubular member having a bearing in the other end thereof for journaling the other end of said screw, means to prevent longitudinal movement of said screw with respect to said tubular member, and means on said screw externally of said tubular member for rotating the screw to produce relative movement between said tubular member and said fixed jaw. 55 60 65

2. A clamp comprising a C-shaped frame having a fixed jaw on one of the legs thereof, the other leg having a portion provided with a screw-threaded opening, a screw extending through said opening, a longitudinally slotted hollow elongated member having a closed end providing a jaw cooperating with said fixed jaw, 70 75

the leg having the portion provided with the screw-threaded opening extending through the slot in said hollow member and cooperating with the walls of said slot to prevent rotation of said 5 hollow member relative to said leg, said screw having one end thereof journaled in said closed end of the hollow member, said hollow member having a bearing in the other end thereof, for journally receiving the other end of said screw, 10 and means adjacent said bearing to prevent longitudinal movement of said screw with respect to said hollow member, said portion having the screw-threaded opening engaging said screw between the end thereof that is journaled in the 15 closed end of said hollow member and the means preventing longitudinal movement of said screw relative to said hollow member, whereby said screw exerts a pull on said C-shaped frame upon rotation thereof in a clamping direction and is 20 put under tension only between the means preventing longitudinal movement of said screw relative to said hollow member and the portion thereof engaging said leg when said clamp is in clamping engagement with the work.

25 3. A clamp comprising a frame having a pair of legs thereon, a jaw on one of the legs, the other leg having a portion provided with a screw-threaded opening, a screw extending through said opening, a longitudinally slotted tubular member 30 having an end wall providing a jaw cooperating with said first-mentioned jaw, the leg having the portion provided with the screw-threaded opening extending through the slot in said tubular member and cooperating with the walls of said 35 slot to prevent rotation of said tubular member relative to said leg, said portion having said screw-threaded opening being mounted within said tubular member, said screw having one end thereof journaled in said jaw forming end of the 40 tubular member, said tubular member having a bearing in the other end thereof for journally receiving the other end of said screw, means to prevent longitudinal movement of said screw with respect to said tubular member, and means on 45 said screw externally of said tubular member for rotating the screw to produce relative movement between said tubular member and said first-mentioned jaw.

4. A clamp having a C-shaped body portion 50 providing a pair of spaced legs, a jaw on one of said legs near the end thereof, the other leg thereof being provided with a screw-threaded opening near the extremity thereof spaced from the portion of the clamp connecting the legs, a 55 member having a screw-threaded stem in screw-threaded engagement with the threads in said opening, means on said member for turning the same, a substantially straight elongated jaw member extending transversely of said other leg 60 and having bearings therein adjacent the opposite ends thereof on opposite sides of said other leg to mount said elongated jaw member on said member having said screw-threaded stem, said elongated jaw member having abutment means 65 thereon extending longitudinally thereof and said other leg having means thereon engaging with said abutment means to hold said elongated member to substantially straight line translation axially of said threaded stem upon rotation of 70 said stem, said elongated jaw member having a clamping face on the end thereof of substantially the area of said other jaw and spaced from said connecting portion, and abutment means on said member having the screw-threaded stem cooper-

ating with the end of said elongated jaw remote from said clamping face to put said elongated jaw under compression and the portion of said stem between said leg and the end of the elongated jaw remote from said clamping face under tension 5 when in clamping engagement with the work.

5. A clamp comprising a C-shaped integral frame having a pair of legs, a jaw on one of said legs, a screw, means on the other leg engaging said screw to advance the same transversely of 10 said leg in either direction, a longitudinally slotted tubular member having end walls, one of said end walls providing a jaw cooperating with said first mentioned jaw, said other leg extending through the slot in said tubular member into said 15 tubular member and cooperating with the walls of said slot to substantially prevent rotation of said tubular member relative to said leg, said tubular member mounted on said screw to house said screw throughout the length of the threads 20 thereon, the end walls of said tubular member mounting the same on said screw on opposite sides of the leg extending into said tubular member, means limiting longitudinal movement of 25 said screw with respect to said tubular member in opposed directions, and operating means externally of said tubular member for producing relative movement between the screw engaging means on the other leg and the screw to produce movement of said tubular member toward and 30 away from said first mentioned jaw, said longitudinal movement limiting means comprising abutment means on said screw engaging the end wall of said tubular member remote from said 35 jaw forming end wall to put said tubular member under compression and the portion of said screw between said leg and the end of said tubular member remote from said jaw forming end under tension when in clamping engagement with the 40 work.

6. A C-clamp comprising a body portion having a pair of legs integral with and projecting from a connecting portion, a fixed flat jaw at the free end of one of said legs removed from said connecting portion, the other leg having a 45 tubular enlargement at its extremity having its longitudinal axis extending transversely of said other leg and being internally threaded, clamping means on said other leg having a flat, rigid clamping face opposite and extending substantially parallel to said flat jaw, said clamping means comprising a screw extending through the opening in said enlargement having threads engaging said internal threads, a longitudinally slotted tubular member receiving said tubular enlargement therein, said slotted tubular member having end walls having means rotatably receiving said screw beyond the opposite ends of said threads thereon to mount said tubular member 55 on said screw and shield said threads from end to end, said end walls lying on opposite sides of the tubular enlargement on said other leg, said other leg extending through the slot in said tubular member and cooperating adjacent said enlargement with the walls of said slot to limit 60 rotation of said tubular member relative to said other leg, means limiting longitudinal movement of said tubular member relative to said screw, and means on said screw externally of said tubular member for rotating said screw, said clamping 65 face being of approximately the diameter of said tubular member, and said entire clamping means being spaced from said connecting portion.

CONRAD J. SCHROEDER.
